DESIGN FOR A CASING FOR A RECORDING MACHINE

Robert J. Niederhauser, Chicago, Ill., assignor to
Myron D. Markley and Joseph M. Markley, Jr.,
Canton, Ohio

Application May 13, 1938, Serial No. 77,171

Term of patent 7 years

To all whom it may concern:

Be it known that I, Robert J. Niederhauser, a citizen of the United States, residing at Chicago, in the county of Cook and State of Illinois, have invented a new, original, and ornamental Design for a Casing for a Recording Machine, of which the following is a specification, reference being had to the accompanying drawing, forming part thereof.

Fig. 1 is a front elevation of a recording machine showing my new design.

Fig. 2 is a top plan view.

Fig. 3 is an end elevation looking toward the right of Fig. 1.

Fig. 4 is an end elevation looking toward the left of Fig. 1.

I claim:

The ornamental design for a casing for a recording machine, as shown.

R. J. NIEDERHAUSER.
